UNITED STATES PATENT OFFICE.

SOREN C. ROCKMAN, OF PHILADELPHIA, PENNSYLVANIA.

COMBINED COAL AND GAS RANGE.

1,155,758.

Specification of Letters Patent.

Patented Oct. 5, 1915.

Application filed September 17, 1914. Serial No. 362,137.

To all whom it may concern:

Be it known that I, SOREN C. ROCKMAN, a citizen of the United States, residing at Philadelphia, in the county of Philadelphia, State of Pennsylvania, have invented certain new and useful Improvements in Combined Coal and Gas Ranges, of which the following is a specification.

My invention relates to coal and gas ranges and it comprises a construction in which means are provided for using or employing either coal or gas as a heating fuel.

One object of my invention is to provide a simple construction of range in which, if desired, gas alone may be employed for cooking purposes and in which coal or other similar fuel may be employed, a fire box of usual construction being provided for that purpose.

If frequently happens that the floor space of kitchens, particularly in the latter day apartments of apartment houses is quite limited so that the matter of space occupied by a range, water heating apparatus, etc. becomes quite an important matter.

It is one of the objects of my invention to provide a combined coal and gas range including gas heated hot water supplying means in the space ordinarily occupied by an ordinary coal range or an ordinary gas range. In accomplishing this purpose I provide the gas heated hot water supplying apparatus in the usually unused space which is found at the back part of the hood of such ranges in rear of the usual hot water tank connected with ranges of this general character. The gas heated hot water supplying apparatus employed by me is supplemental to the ordinary or normal hot water supplying apparatus and may be used simultaneously therewith or independently thereof as may be found to be convenient.

In the accompanying drawings I have illustrated one form of a combined coal and gas range embodying my invention but it is to be understood that changes in the details of construction may be made within the scope of the claims without departing from my invention.

In the drawings:—Figure 1 is a view in front elevation of a range embodying my invention and also showing a portion of the front part of the stove broken away and certain parts thereof in section: Fig. 2 is a view in side elevation of a range embodying my invention: Fig. 3 is a vertical trans-

verse sectional view of the gas heated hot water compartment such view showing the coil structure: Fig. 4 is a sectional view of a gas heated hot water compartment taken at right angles to the view shown in Fig. 5; and Fig. 5 is a transverse sectional view taken on line 7—7 of Fig. 4.

Referring to the drawings, 1 designates the body portion of the range including the oven 2 and fire box 3, the former being preferably spaced from the outside walls of the body part of the range to provide for the passage of products of combustion and the latter, that is the fire box, suitably bounded on one side by the customary water back 4. The oven 2 is also spaced from the top 5 of the range forming a space which is adapted to receive the hot products of combustion from the fire box 3 and which is also provided with auxiliary gas burners 7, (one only of which is shown) underneath the pot holes in the top plate of the stove. On opposite sides of the burner 7 dampers or valves 8 and 9 are provided, forming a chamber 6 in the space above the oven 2. The damper or valve 8 should be closed and the damper or valve 9 opened when it is desired to use the gas burner 7 for any purpose. At such time the products of combustion from the fire box 3 are cut off from the chamber 6 as is clear from an inspection of Fig. 1 of the drawings.

When the burner 7 is being used the valves 8 and 9 should occupy the position shown in Fig. 1 of the drawings the opening 10 being open for supplying air necessary to the combustion of the burner 7. When the burner 7 is not in use and heat is being employed from the fire box only the valve or damper 9 should occupy a vertical position closing the opening 10 while the valve or damper 8 should occupy a horizontal or partially horizontal position to admit the heat freely from the fire box 3 into the chamber 6.

In order to prevent ashes, soot, etc. from collecting in the perforations of the burners 7, I provide plates 10^a which rest upon the tops of said burners. These plates are provided with perforations (not shown) and may slide or turn with respect to said burners, so as to place said perforations either in or out of registry with the perforations of the burners. To prevent accidental displacement of the plates 10^a from the burners they are provided with flanges 10^b which

extend downwardly around said burners. To limit the sliding or turning movement of said plate I provide the short slots 10^a in the respective flanges through which pins 5 on the burners project.

11 designates a gas burner located in the lower portion of the body part of the stove and positioned beneath the oven 2 so that the latter may be heated satisfactorily in 10 case the gas burner is used instead of a coal or other fuel burning fire box. The gas burner 11 receives its gas from the conduit 12 which is connected to the gas supply pipe 13 and is controlled by any well known 15 type of valve 14. The supply pipe 13, in the present instance, extends vertically at one side of the range structure and is provided with a pair of branches 15 and 16 controlled respectively by hand valves 17 20 and 18, as will be readily understood. The branch 15, in the present instance, extends within the hood 19 which is positioned as customary above the top 5 of the range where the said branch terminates in a 25 burner 20 located beneath the baking compartment 21. The branch 16 also extends within the hood and terminates in a burner 22 located in the top part of the broiler compartment 23, as will be understood.

30 24 designates the flue which communicates at its lower end with the combustion chamber of the body part 1 of the range and passes upwardly at the rear of the hood back of the broiler compartment 23. This 35 flue conducts the products of combustion to a suitable chimney or vent, not shown.

In the present instance, I have utilized the usual waste space at the rear of the 40 water tank or boiler 25 and also extending in rear of the broiler compartment 23 by providing a plate or partition 26 forming with the walls of the hood a heating chamber 27 containing the water heating coil 28 which is heated by means of the gas 45 burner 29. This burner is supplied with gas from a branch pipe 30 leading from the pipe 15 and controlled by a suitable valve so that it may be operated independently of the burners 20 and 22. The bottom 30^a of the chamber 27 is closed so as to prevent the falling of particles from the chamber 27 on to the top of the stove underneath the hood. It will be understood that as usual the space upon the top of the 50 stove and underneath the hood is free in order that vessels containing cooking or cooked food may be pushed to the rear of the top of the stove. If the bottom of the chamber 27 were provided with an opening 55 or openings it might happen that particles of foreign matter would drop down therethrough into the food contained in such vessels. The air for supplying oxygen for combustion to the burner 29 is supplied 60 through an opening 30^b in the rear wall of

the chamber. The gases from the chamber are permitted to escape through the opening 41 through the top of the chamber.

31 and 32 designate respectively circulating pipes for conveying water from the water back 4 to the boiler or tank 25 in the customary manner, the heated water ascending in the pipe 31 while the water of lower temperature descends in the pipe 32 to the bottom of the water back 4. The water supply pipe 33 leading from the house main connects with the tank 25 at a suitable point above the point of connection therewith of the pipe 32, as is clearly shown in Fig. 2 of the drawings. The said pipe 33 also has a branch 34 which communicates or connects with the lower end of the coil 28. The upper end of the coil 28 is connected with a receptacle 40. A pipe 36 leads from the receptacle 40 to a pipe 37 from which hot water may be drawn through the hot water spigot 38. It may happen that the water in the tank 25 is heated to a considerable degree by means of the heat in the fire box 3 so that it is unnecessary to employ the water heating coil 28 for supplying such hot water as may be needed. In other words, the water in the coil 28 is allowed to remain cool. In such case, unless means were provided to prevent such occurrence, it might happen that hot water would escape from the tank through the pipe leading from the top part thereof shown in Fig. 2 and pass into the receptacle 40. To prevent such occurrence 100 I have provided the valve 38^a in the pipe 36 leading from the receptacle 40. The receptacle 40 is situated immediately above the top of the heating chamber 27 and in the path of the hot combustion products 105 which are discharged through the opening 41. This receptacle is adapted to hold a relatively small body of water which may be heated quickly for the purpose of supplying hot water quickly as when a housewife might desire a single dish pan of water for some special purpose. If this should be the case, she would ignite the burner 29 and the heat therefrom would quickly heat the water in the coil 28 and in the receptacle 40, the two together holding the required quantity of water. It will thus be seen that when a relatively small quantity of water is desired it may be quickly furnished by the means just described. At such time if the valve 42 is closed no water can pass to the delivery pipe 37 from the tank 25 but is free to pass to such pipe from the receptacle 40 and the coiled pipe 28 provided the valve 38^a is open as it must be when it is desired to draw water from the said coil 28 and receptacle 40.

The receptacle 40 is provided with a diaphragm cover 43 serving a purpose which

may be described in connection with the operation of the gas burner 29 to which I have previously referred. The burner 29 for heating the coil 28 in the chamber 27 preferably is automatically controlled by the expansion and contraction of the coil 28 and its adjuncts, including an outward movement or a movement of expansion of the diaphragm 43.

10 For the purpose of controlling the supply of gas to the burner I have provided a cut-off valve 44 which is adapted for sliding movement across the discharge outlet of the Bunsen burner which valve is carried by a lever 46 fulcrumed at 47 to a suitable bracket 48 or the like which is supported upon any suitable part of the range structure.

15

49 designates a rod connected at one end
20 to the lever 46 near the pivot of the latter,
said rod having at its opposite end a laterally disposed arm 50 which has threaded
25 engagement with a stud bolt 51 the operating
end of which bears against a suitable
abutment 52 which is situated upon the central
part of the diaphragm 43. In case of ex-
cessive pressure due to the overheating of the
water within the receptacle 40 the diaphragm
30 43 is forced outwardly thereby actuating the
arm 50 to shift the rod 49 longitudinally and
consequently impart pivotal movement to
the lever 46 to cause a sliding movement
35 of the valve 44 across the outlet 45 of the
burner to thereby cut down the supply of
gas in the desired manner. As an adjunct
to this automatic control I have also em-
ployed a second arm 53 which is suitably
40 secured to the rod 49 intermediate its ends
and projects through an opening 54 in the
casing of the chamber 37 and into contact
with the top part of a convolution of the
coil 28 so that by expansion of the latter
45 the rod 49 will also be moved longitudinally
to effect movement of the cut-off valve 44 to
cut down or retract the supply of gas to the
burner in the manner already described.
When the supply of gas is thus restricted the
50 burner flame consequently will be decreased
so that the heat generated will be likewise de-
creased and the amount of heat supplied to
the coil 28 and the receptacle 40 and the
water contained therein will be decreased
55 so as to prevent an explosion of any of the
parts including the chamber 40 and the coil
contained in the gas heated chamber.

In order to prevent a movement of the cut-off valve 44 a sufficient distance to completely close the burner opening 45, I have provided means for limiting the longitudinal movement in one direction of the rod 49. The means provided for this purpose consists of a bracket 56 secured upon the side of the range structure, as shown in Fig. 3 of the drawings, which bracket is provided with an opening through which the rod 49

extends. The said rod 49 is provided at this bracket with a screw-threaded portion upon which is secured an adjustable nut 57. This nut is located on the rod 49 beneath the bracket 56 and normally at such distance below the bracket 56 that it permits a sufficient upward movement of the rod 49 to cause movement of the valve 44 a sufficient distance to greatly restrict the burner opening 45, leaving just sufficient passage-way 75 to provide for a pilot flame or light. It would be dangerous to permit movement of the cut-off valve 44 a distance sufficiently great to completely close the opening 45 and thereby cut off entirely the supply of gas. 80 If this should happen gas would be permitted to escape from the burner and through the chamber 27 into the kitchen chamber as soon as the coil and the water in the receptacle 40 became somewhat cooled. 85

Although I have shown in Fig. 5 a burner of novel shape and construction which I have found to be very efficient, it will be understood that in so far as my invention is broadly concerned a burner of any other suitable construction may be employed.

I claim:—

1. A kitchen range comprising a fire box, a water back in operative relation to said fire box, a hood, a hot water tank for receiving water from said water back, said tank being supported upon said hood and being spaced from the rear wall thereof, a gas heated hot water supplying apparatus situated in the space back of said tank, and means whereby water may be drawn either from the tank or the said hot water supplying apparatus or from both simultaneously, substantially as described. 95 196

2. A kitchen range comprising a fire box 105
in its main body portion for burning fuel
such as coal, a water back in operative re-
lation to said fire box for heating water,
a water holding tank for receiving hot wa-
ter from said water back, a relatively small 110
hot water holding receptacle, a heated coil
for supplying hot water to said receptacle,
and means whereby water may be drawn si-
multaneously from said tank and receptacle
or independently from either one at differ- 115
ent times.

3. A kitchen range comprising a hood, a hot water tank supported upon said hood, the said tank being spaced from the back of said hood, a heating chamber interposed 120 between the said tank and the said back, a coiled pipe situated in the said heating chamber, means for supplying cool water to said coiled pipe, a gas burner for heating the said coiled pipe and the water therein, a receptacle having connection with the upper end of said coiled pipe, a pipe for delivering hot water from the said tank and the said coiled pipe and receptacle and means whereby hot water may be delivered simultaneously 125 from the said tank and the said receptacle.

ously or independently from the said tank and from the said coil and receptacle.

4. A kitchen range comprising a hood, a hot water tank supported thereon and provided with a pipe for delivering water therefrom, said tank being spaced from the back of said hood, a heating chamber interposed between said tank and the back of said hood, a coiled pipe in the said heating chamber, means for supplying cool water thereto, a gas burner for heating said coiled pipe and the water therein, a receptacle having connection with the upper end of said coiled pipe for receiving hot water therefrom, a connection between the said coiled pipe and the said receptacle whereby hot water may be supplied from said coiled pipe and the said receptacle to the delivery pipe leading from said tank, and independent means for closing the connections between the delivery pipe and the tank and the said coiled pipe and receptacle, substantially as described.

5. A kitchen range comprising a hood, a hot water tank supported upon said hood and having a delivery pipe for delivering water therefrom, the said tank being spaced from the back of said hood, a heating chamber interposed between the said tank and the back of said hood, a gas burner situated in the lower part of said chamber, a coiled pipe situated in the said heating chamber above the said burner, means for supplying cool water thereto, a receptacle having connection with the upper end of said coiled pipe for receiving hot water from the latter, connections between the said receptacle and the said coiled pipe and the said delivery pipe leading from the said tank, and means having engagement with the said coiled pipe and with the said receptacle and being actuated thereby for controlling the passage of gas to the said burner.

6. In a kitchen range, the combination of a hood, including a broiler, with means for heating the same, a hot water tank supported upon said hood, said broiler and said tank being spaced from the back part of said hood, means comprised in said range for supplying hot water to said tank, a heating chamber interposed in the space between the said broiler and the said tank and the back of said hood, a gas burner situated in the lower part of said heating chamber, a coiled pipe in the said heating chamber, means for supplying cool water to said coiled pipe, and means interposed between the said coiled pipe and the said burner and actuated by the expansion and contraction of said coiled pipe for controlling the gas supplying passage-way therefor.

7. The combination with the superstructure of a range having a hot water containing tank, of a water heating means situated within and secured to the said superstruc-

ture, a valve for preventing the passage of hot water from the said tank to the said water heating means, and a hot water delivery pipe common to the said tank and to the said water heating means for delivering hot water either simultaneously or independently from the said tank and from the said water heating means.

8. A kitchen range structure comprising a coil for heating hot water, a chamber within which the said coil is situated, a gas burner situated in the said chamber underneath the said coil for heating the latter, a movable member for controlling the passage-way for the gas to said burner, a controlling member having connection with said movable member for occasioning movement of the latter, means operatively connecting said controlling member to the said coil whereby contraction and expansion of the latter occasion movement of the said controlling means and adjustable means for limiting the extent of movement of the said controlling means in one direction.

9. A kitchen range structure comprising a water receiving receptacle, a chamber in which the said receptacle is situated, a gas burner situated in said chamber for heating the said receptacle, a pivoted lever for controlling the passage-way for the gas to said burner, a controlling rod having connection with said pivoted lever, connecting means between the said rod and the said receptacle whereby expansion and contraction of the latter occasion movement of the said rod to thereby cause movement of the said pivoted lever to control the gas passage-way, and adjustable means for limiting movement of the said rod in one direction.

10. In a combined coal and gas range having a hood, a vertical fire chamber situated in the rear part of said hood having a closed bottom and an open top, the latter permitting the escape of the gases of combustion from said chamber and said chamber having an opening in its side for admitting air thereto, a burner secured to the bottom of said fire chamber, a gas inlet to said burner at right angles to said air inlet, a coil above said burner said coil being secured to said chamber adjacent to the inlet to said burner, a cold water supply leading to said coil, a tank secured to the top of said coil, and an outlet from said tank.

11. In a combined coal and gas range having a hood, a vertical fire chamber situated in the rear part of said hood having a closed bottom and an open top the latter permitting the escape of combustion gases from the said chamber and said chamber having an opening in its side for admitting air thereto, a burner secured to the bottom of said fire chamber, a gas inlet to said burner at right angles to said air inlet, a

coil above said burner said coil being secured to said chamber adjacent to the inlet to said burner, a cold water supply leading to said coil, a tank secured to the top of said coil, an outlet from said tank, means interposed between said coil and said burner actuated by the expansion and contraction of said coil for regulating the supply of gas to said burner, and adjustable means for adjusting and limiting the extent of movement of said gas regulating device.

12. In a range having a hood comprising a passage for a chimney pipe, a vertical heating compartment at one end of said hood having a closed bottom for preventing dirt from escaping therefrom and also having an open top, a heating coil secured to one end of said hood, a bifurcated burner below said coil and secured to said hood, a gas inlet to said burner said gas inlet being secured to the aforesaid end of said hood, a tank secured to the upper end of said coil, an outlet from said tank, a water inlet to the coil and an air inlet leading through said hood to the bottom of said fire chamber.

13. In a range having a hood comprising a passage for a chimney, a vertical fire

chamber adjacent to said chimney said chamber having a closed bottom and an open top and also having an air inlet in the rear 30 of said hood, a coil secured to the end of said hood, a bifurcated gas burner below said coil secured near the bottom of said chamber, the bifurcation or separation of said burner being in alinement with the 35 said air inlet for increasing the efficiency of the ready admission of air to said burner, a gas inlet to said burner leading to the bifurcated or separated portions thereof, a mixer in said gas inlet, means for automatically partially closing the gas passage in said gas inlet, means for adjusting and regulating said last mentioned means, an inlet for supplying cool water to the coil at the end of the hood, and a tank at the upper 45 end of the coil said tank having an outlet.

In testimony that I claim the foregoing as my invention, I have hereunto signed my name this 14th day of September, A. D. 1914.

SOREN C. ROCKMAN.

In the presence of—

FLORENCE DEACON,
CARRIE E. KLEINFELDER.
